(57) CLAIM

I claim the ornamental design for a handheld bag holder, as shown and described.

DESCRIPTION

FIG. 1 is an isometric top, front view of the handheld bag holder showing my new design in use, having a bag installed upon the bag holder, wherein broken lines are used for illustrating the bag and hand grip details and do not form any part of the design;

FIG. 2 is an isometric top, front view of the handheld bag holder thereof;

FIG. 3 is an isometric bottom, front thereof;

FIG. 4 is a front view thereof;

FIG. 5 is a left side view thereof;

FIG. 6 is a rear view thereof;

FIG. 7 is a right side view thereof;

FIG. 8 is a planar top view thereof;

FIG. 9 is a planar bottom view thereof;

FIG. 10 is a magnified elevation side view of a portion of the handheld bag holder detailing a rear tooth; and,

FIG. 11 is a magnified elevation rear corner view of a portion of the rear tooth thereof.
